Primary Examiner — Keli L Hill(74) *Attorney, Agent, or Firm* — Fulwider Patton LLP(57) **CLAIM**

The ornamental design for an electric toothbrush, as shown and described.

DESCRIPTION

FIG. 1 is a left side elevational view of an electric toothbrush showing my design.

FIG. 2 is a front side elevational view thereof.

FIG. 3 is a right side elevational side view thereof.

FIG. 4 is a rear side elevational view thereof.

FIG. 5 is a top plan view thereof.

FIG. 6 is a bottom plan view thereof.

FIG. 7 is a rear perspective view thereof.

FIG. 8 is a front perspective view thereof; and,

FIG. 9 is an alternate front perspective view thereof, shown mounted in a base and including an additional toothbrush head.

The broken lines shown are included for the purpose of illustrating portions of the electric toothbrush that form no part of the claim.
